UNITED STATES PATENT OFFICE.

HAROLD E. YARROW, OF GLASGOW, SCOTLAND.

FUNNEL OF SUBMARINE VESSELS.

1,260,848.

Specification of Letters Patent. Patented Mar. 26, 1918.

Application filed October 30, 1917. Serial No. 199,308.

To all whom it may concern:

Be it known that I, HAROLD EDGAR YARROW, a subject of the King of Great Britain, residing in Glasgow, Scotland, have invented 5 certain new and useful Improvements Relating to Funnels of Submarine Vessels, of which the following is a specification.

It has lately been found possible to reduce the size of the funnels of vessels, more 10 particularly of the submarine type driven by oil fuel, by increasing the pressure of the air supply to the furnaces.

The small size of the funnel allows means 15 to be employed for housing the funnel when the vessel is submerged, which were not practically applicable to the larger size of funnel required for modern practice.

According to the present invention, the 20 funnel is made telescopic, and when the vessel is submerged, is lowered into a receptacle provided in the steam drum.

In the accompanying drawing which represents a cross section through a boiler compartment of a submarine, A is the shell of 25 the submarine, B₁, B₂ external water ballast tanks, C a steam drum, D₁, D₂ water drums, E₁, E₂ the tubes, F the uptake, G the funnel, which can be lowered, as shown by the full 30 lines in the figure, into a pocket H provided

in the steam drum, the aperture in the shell 30 being closed by a valve I. The funnel is shown in the raised position by dotted lines.

The housing of the funnel in the steam drum in the manner described also provides 35 a firm foundation for the base of the funnel to rest upon when it is in the housed position and has to be made water-tight.

I am aware that telescopic funnels have been proposed for the comparatively small 40 powered submarine vessels first constructed, and I do not broadly claim the use of such funnels.

Having thus described the nature of the 45 said invention and the best means I know of carrying the same into practical effect, I claim:—

A telescopic funnel for a submarine vessel adapted to be lowered when the vessel is submerged into a housing provided in the 50 steam drum.

In testimony whereof I have signed my name to this specification in the presence of two subscribing witnesses.

HAROLD E. YARROW.
